[57] CLAIM

The ornamental design for a solid state planar sensor, as shown and described.

DESCRIPTION

FIG. 1 is a perspective view of a solid state planar sensor showing our new design;

FIG. 2 is a top plan view;

FIG. 3 is a bottom plan view;

FIG. 4 is a side view, the opposite side view being a mirror image thereof;

FIG. 5 is a front view; and

FIG. 6 is a rear view.
